Primary Examiner — John Windmuller(74) *Attorney, Agent, or Firm* — Klein, O'Neill & Singh, LLP(57) **CLAIM**

The ornamental design for a pillow speaker with controls for an A-V display, as shown and described.

DESCRIPTION

FIG. 1 is a front elevation view of a pillow speaker with controls for an A-V display, in accordance with our new design;

FIG. 2 is a side elevation view of the pillow speaker with controls for an A-V display shown in FIG. 1, taken from the right side of FIG. 1;

FIG. 3 is a side elevation view of the pillow speaker with controls for an A-V display shown in FIG. 1, taken from the left side of FIG. 1;

FIG. 4 is a rear elevation view of the pillow speaker with controls for an A-V display shown in FIG. 1;

FIG. 5 is a bottom plan view of the pillow speaker with controls for an A-V display shown in FIG. 1; and,

FIG. 6 is a top plan view of the pillow speaker with controls for an A-V display shown in FIG. 1.

The broken lines represent environmental structure that forms no part of the claimed design.
